[57] **CLAIM**

The ornamental design for a frame for a vehicle windshield wiper unit, as shown and described.

DESCRIPTION

FIG. 1 is a perspective view of a frame for a vehicle windshield wiper unit showing my new design;

FIG. 2 is a top plan view thereof;

FIG. 3 is a bottom plan view thereof;

FIG. 4 is an elevational view thereof showing the side opposite that shown in FIG. 1; and,

FIG. 5 is an end elevational view looking from the right of FIG. 4, the opposite end being a mirror image thereof.

The broken line showings of various parts of the windshield wiper, shown in FIGS. 1 through 5, are for illustrative purposes only and form no part of the claimed design.
